(57) **CLAIM**

The ornamental design for a crane, as shown and described.

DESCRIPTION

This application contains at least one drawing executed in color. Copies of this patent or patent application publication with color drawing(s) will be provided by the Office upon request and payment of the necessary fee.

FIG. 1 is a front perspective view of a design for a crane according to the present disclosure.

FIG. 2 is a rear perspective view of the crane of FIG. 1.

FIG. 3 is a right side view of the crane of FIG. 1.

FIG. 4 is a left side view of the crane of FIG. 1.

FIG. 5 is a front view of the crane of FIG. 1.

FIG. 6 is a rear view of the crane of FIG. 1; and,

FIG. 7 is a top view of the crane of FIG. 1.

The solid lines in FIGS. 1-7 illustrate a design for a crane according to the present disclosure. A bottom view is not shown because there are no claimed features on the bottom view other than those features included in the views provided. The break lines in FIGS. 1-6 illustrate the extension of the crane. The extension of the crane beyond the break lines forms no part of the claimed design.
